UNITED STATES PATENT OFFICE.

GUSTAV R. BAUER, OF OCEANPARK, CALIFORNIA.

AMALGAMATOR.

1,114,573.

Specification of Letters Patent.

Patented Oct. 20, 1914.

Application filed May 14, 1913. Serial No. 767,589.

To all whom it may concern:

Be it known that I, GUSTAV R. BAUER, a citizen of the United States, residing at Oceanpark, in the county of Los Angeles and State of California, have invented new and useful Improvements in Amalgamators, of which the following is a specification.

This invention relates to amalgamators, and the principal object is to provide a sluice-way with a plurality of amalgamating plates and screens, certain of which are removable while the apparatus is in operation.

It is also an object to provide an amalgamator of the type formed in a sluice-way with a plurality of revoluble amalgamating members which are removable, interposed between which are a plurality of stationary amalgamating screens.

It is further object to provide an amalgamating apparatus carried in a sluice-way with a return sluice or flume adapted to carry away debris which is permitted to escape from the sluice-way before reaching the amalgamating devices.

In the drawings accompanying this specification and forming therewith the application for Letters Patent: Figure 1 is a longitudinal sectional view of the amalgamator. Fig. 2 is a plan view of the same. Fig. 3 is a perspective detail of the paddle-wheels. Fig. 4 is a perspective view of one of the cylindrical amalgamating screens. Fig. 5 is a section on the line 5—5 of Fig. 2 viewed in the direction indicated by the arrows. Fig. 6 is a detail plan view of a modification of the riffle box. Fig. 7 is a perspective detail view of one of the metallic spoon shaped riffles.

More specifically in the drawings, 10 designates the terminal end of a flume into which has been thrown river sand or tailings from a mill bearing fine or flour gold, this flume preferably ending in an end wall 11, having an opening in its floor, which drops into the riffle box 12 provided with transversely disposed riffle bars 14, this riffle box being interchangeable according to the type of material used and forms of connection to the sluice-way 16 from the flume 10, the riffle box being preferably supplied with a deflecting board 15 in which are cut riffles capable of segregating larger particles of the metal to be saved.

The sluice-way 16 is preferably, as shown, of elongated construction common to this

type of separators, having a floor 17 which is preferably formed with a slotted opening 18 adjacent the connection to the riffle box 12, a chamber 19 being formed thereunder by means of suitable inclosing walls, the exit from this chamber being controlled by a slide 20. The floor 17 is preferably inclined to the proper degree so that the water carried thereon will readily flow at the desired speed, and from a point just below the sand opening 18 a copper plate 21 is inserted in the floor and carried the full length, this plate being plated in the usual manner by silver and covered with a coating 70 of amalgam so that the particles of amalgamable metal will be incorporated therewith. To further secure the amalgamation of these particles floating in the current a plurality of paddle-wheels 22 are provided having 75 shafts 23 which extend in suitable bearings in the side walls of the sluice-way 16, a plurality of paddle blades 24 being mounted thereon, the wall itself being adapted to be encircled and surrounded by a cylindrical 80 sleeve 25 preferably formed of copper wire screen of suitable mesh which is suitably treated with the amalgam.

To further insure the complete removal of all the amalgamable material from the ingredients carried in the sluice-way vertical guide-ways 26 are provided into which are inserted transversely disposed screen plates 27, these plates being also formed of copper screen and provided with amalgam in the 90 usual manner. Below the desired number of amalgamating wheels and screens a gate 28 is provided to regulate the amount of flow thereby, or entirely cut off the latter and throw the water and material carried 95 thereby into openings 29 adjacent and above the gate, which communicate with chambers 30 formed on either side by suitable inclosing walls having a floor 31 which extends from side to side of the end walls and is inclined in relation to the horizontal and in the reverse direction to that of the floor 17 so that the water will attain a somewhat greater velocity and the exit 32 will be disposed adjacent the point where the debris 100 falls from the chamber 19 and carries this latter away from the vicinity and into the stream bed or other location provided.

The openings 29 are provided with gates 33 and to properly carry the flow the rearwardly disposed portions of these chambers and the width of the floor 31 is materially 110

increased so that the inclosing top 34 on each side is of the triangular form shown.

The amalgamating floor 21 is extended preferably some distance beyond the gate 28 5 and terminates in a trough 35 which is transversely disposed to the sluice-way and is provided with a riffle board 36 to further insure the collection of particles of metal which may have escaped the amalgamating 10 process.

Depending on the character of the material operated on, a riffle box of the type shown in Fig. 6 is sometimes used, on the floor of which, instead of the transverse 15 riffles, are mounted a plurality of staggered spoons 37, which are secured by suitable rivets 38 to the floor so that the material is agitated to a greater extent and materially assists in the operation.

20 In the operation of this device the gold bearing material is carried from the flume 10 into the riffle box 12 and from this point of agitation is carried into the sluice-way 16 containing the amalgamating devices and 25 plates. The floating gold being suspended in passing through the riffle box is carried by the opening 18 where larger particles of debris, as sand, fall into the chamber 19 and are carried away with a certain amount 30 of the water allowed to pass therethrough and would ordinarily block up under the device, this being prevented by the flow of water through the gates 33 and chambers 30 and impinging upon the debris deposited 35 opposite the exit 32.

In passing down the sluice-way the gold carried by the water meets with the screens 25 as they are revolved by the paddle-wheels, and as these screens take up their full 40 amount of metal they may be left out or removed separately, and wheels that have been newly coated placed in their stead so that the operation can be carried on continuously and efficiently and the full use of water obtained without any delay incident to the 45 operation.

The plates 27 may also be left out as required and the gate 28 may be closed to clean out the trough 35, or to throw the full 50 stream of water through the chamber 30 and against the sand passing through the opening controlled by the slide 20.

What I claim is:

1. An amalgamating apparatus, comprising 55 a sluice-way having a flat amalgamating

plate on the bottom thereof, a cylindrical amalgam carrying screen revolvably mounted in the sluice-way and extending transversely thereof with the lower point of the periphery thereof spaced a short distance from the 60 flat amalgamating plate, and means controlled by the flow of liquid through the sluice-way for rotating said screen.

2. In an amalgamator, an inclined sluice-way having a flat bottom and vertical 65 side walls, a flat amalgamating plate on the bottom of said sluice-way, a paddle wheel revolvably and removably mounted in the side walls of the sluice-way and extending transversely of the latter, 70 said paddle wheel adapted to be rotated by the flow of liquid through the sluice-way, an amalgam carrying screened cylinder removably mounted on said paddle wheel with the periphery thereof spaced a short distance 75 from the flat amalgamating plate, and means at the lower end of the sluice-way for regulating the flow of liquid therethrough and thereby regulate the rotation of the paddle wheel. 80

3. In an amalgamator, an inclined sluice-way having a flat bottom and vertical side walls, a flat amalgamating plate on the bottom of said sluice-way, a paddle wheel revolvably and removably mounted in the side 85 walls of the sluice-way and extending transversely of the latter, said paddle wheel adapted to be rotated by the flow of liquid through the sluice-way, an amalgam carrying screened cylinder removably mounted 90 on said paddle wheel with its periphery spaced a short distance from the flat amalgamating plate, and means at the lower end of the sluice-way for regulating the flow of liquid therethrough and thereby regulate 95 the rotation of the paddle-wheel, said sluice-way formed with an opening in its bottom adjacent its upper end to permit the passage of heavy materials therethrough to prevent said materials being carried over the amalgamating plate and against the cylindrical screened cylinder. 100

In witness that I claim the foregoing I have hereunto subscribed my name this first day of May, 1913.

GUSTAV R. BAUER.
